No. 36,750.

Patented January 26, 1904.

UNITED STATES PATENT OFFICE.

OTTO KRAUSE, OF NEW YORK, N. Y.

DESIGN FOR A LIQUID-CONTAINER.

SPECIFICATION forming part of Design No. 36,750, dated January 26, 1904.

Application filed December 16, 1903. Serial No. 185,446. Term of patent 14 years.

To all whom it may concern:

Be it known that I, OTTO KRAUSE, a citizen of the United States, and a resident of the borough of Manhattan, city, county, and State of New York, have invented a new, original, and ornamental Design for a Liquid-Container, of which the following is a specification.

Figure 1 of the accompanying drawings is

an elevation of a liquid-container embodying my new design, and Fig. 2 is a plan thereof.

I claim as my invention—

The new, original and ornamental design for a liquid-container substantially as shown.

OTTO KRAUSE.
